VEHICLE RUNNING GEAR.

No. 309,576.

Patented Dec. 23, 1884.

UNITED STATES PATENT OFFICE.

BENJAMIN C. SHAW, OF TOLEDO, OHIO.

VEHICLE RUNNING-GEAR.

SPECIFICATION forming part of Letters Patent No. 309,576, dated December 23, 1884.

Application filed July 30, 1883. (No model.)

To all whom it may concern:

Be it known that I, BENJAMIN C. SHAW, a resident of Toledo, Lucas county, Ohio, have made certain new and useful Improvements in 5 Wagons, a description of which is set forth in the following specification, reference being made to the accompanying drawings, in the several figures of which like letters indicate like parts.

10 My invention relates to the construction of wagon-gearings; and it consists, first, in an easily-adjusted portable tongue; second, a single supporting center bar, upon which the rear end of the tongue rests in metal socket-bands instead of between the jaws of hounds or futchells; third, in the adjustment of independent draw bars and rods equalizing the 15 draft of the team to the unevenness of the road; fourth, double reaches solidly attached 20 to the front bolster in the usual way, but to the hind bolster by means of extension-bars, readily adjusting the length of the coupling to the wants of the service; and these objects I accomplish by the mechanism herein described 25 and illustrated.

In the drawings, Figure 1 represents a side view of a wagon embodying my improvements, the hubs and spokes and spindles being removed to give a better view of the gearing. 30 Fig. 2 is a top or plan view of the gearing of a circle-tracking wagon embodying my improvements with the tongue removed, shown when turning a curve. Fig. 3 is a detail side view, on a larger scale, of the tongue and its 35 supports, connecting-rods, braces, and the connections with the front axle. Fig. 4 is a cross-section of the stop-lug S^2 , which holds the tongue in place. Fig. 5 is a side view of the draw-bar Db , draw-bolt Dbt , and hammer-40 strap brace Hsb . Fig. 6 is a top view of the draw-bar Db , showing the slot in the rear end.

In detail, Pt represents the rear section of the loose portable tongue, held in place by the loop-band Lb and the stop-lug Sl underneath 45 the socket-band Lb , the stop-lug rising up out of the support-bar Cb and fitting into a recess or cavity formed on the under side of the tongue Pt , which prevents the displacement of the latter while traveling on the road. The 50 socket-band Sb is provided with a rear vertical stop-band with a lug projecting to the rear, and is bolted to the center bar, Cb . This

forms a permanent stop or holdback, against which the rear end of the tongue rests. When the team is holding the wagon back with the 55 breast yoke or chains, the front end of the tongue will be raised high enough in the loop-band Lb to raise the recess on the under side above the stop-lug Sl , but when the backward pressure ceases the tongue will resume its 60 proper resting-place. The loop-band Lb , being higher than the tongue is deep, gives room to insert the latter through it into the socket-band Sb and over the stop-lug Sl , and when the tongue is lowered into place it is 65 locked there. To remove it, seize the tongue in the middle and raise the front end until the stop-lug is disengaged, and the tongue may then be drawn out.

Cb represents a center bar or wooden-tongue-support bar wider than the tongue, and it is gained into and across the front axle at right angles and flush with the top side of the stock. It is supported by the lateral brace-hounds Bh in front, as shown in Fig. 2, and rests on 75 the swing-bar Swb between it and the loop Lp at the rear, and is connected with the pivot-rod Pvr at the joint 3 when used in a circle-tracking wagon. On the under side of this bar Cb are loop-staples Ls and Ls' , through which 80 passes the draw-bar Db , which is inserted from the front, closely fitting in Ls' , but having considerable lateral room in Ls . This draw-bar Db is pivoted in the rear loop-staple, Ls' , and has a long slot in the rear end, as shown 85 in Fig. 6. Its head is made with a solid draw-bolt, Dbt , to which the double-trees are attached.

Dr represent double-forked draft-rods having rigid head and leader-hook Lh , with links 90 l on each end. The junction or head at its front center has a hole through which the draw-bolt passes. For light vehicles the leader-hook can be omitted. The hammer-strap brace Hsb is bolted at the rear to the draw-bar Db , and being put on over the end of the draw-bolt Dbt , the nut of the latter is screwed on. The links l are attached to the permanent hooks h on either side the front axle, and there make the attachment of the team, and the 95 draft is applied direct to the shoulders of the front axle of the wagon. The result of this combined mechanism is the equalization of the draft of the team when hauling the wagon 100

over uneven surfaces. For example, when the forward wheel of a vehicle on the right side strikes an obstruction the front end of the tongue is jerked to the right, and in the common mode of attachment the more the near horse pulls on the eveners the greater the tendency is, especially when pulling by a stay-chain to crowd the point end of the tongue farther to the right. If the right wheel is in a mud-hole, the off horse will likely have poor footing, and can render but little assistance, and often the horse is balked at this unfortunate juncture. Now, if the near horse, who is probably on better ground, materially assists in extricating the wagon, he must be turned by the check-rein at a sharp angle from the direct line of travel, that he may, with the tongue and yoke-chains, pull the tongue to the left, while with the traces he undertakes to pull the wagon out of the hole. But when my draft devices are used under similar circumstances, when the right wheel strikes the obstruction, the instant the lateral tendency of the pole commenced the whole force of the team, if necessary, would be applied directly to the shoulder of the axle whose wheel was unevenly obstructed, the left link would slack up, and the lateral tendency of the tongue from the direct line of travel would be arrested. In this manner the whole force of the team is applied direct to the resistance and the tongue will not be swerved any great amount from the line of travel and ceases to be a baulder of the legs of the horses. On a circle or curved tracking wagon, when the right front wheel has passed the obstruction and the right hind wheel comes in contact with it, the tendency is to jerk the point of the tongue to the left; but with my equalizing devices the force of the draft is instantly shifted from the right to the left draft-rod and slackens up on the right link, by which means resistance to lateral movement is made by the center bar holding the central pivot in line with the direction of travel, and the hind wheel is pulled forward through or over the obstruction, as the front one was, by the direct equalization of the draft on the forward axles, and indirectly on the central pivot-bar, *Cb*, compelling the direct forward movement of the

right hind wheel, and vice versa. Behind the rear axle and upon the pivot-rod *Pvr* is placed a band, *Mb*, with set-screw, for limiting the movement of the pivot-rod, serving as a stop for that purpose. This pivot-rod *Pvr* forward of the rear axle passes through the head of a pair of hounds, and is jointed at 3 to the center bar, as shown in Fig. 2, and is more fully shown and described in Letters Patent No. 216,354, issued to me on the 17th day of June, 1879. In Fig. 2 these parts are marked 4, 5, and 6:

Wi are wearing-irons, which are bolted to the hounds and will be found to be an improved substitute for the common circle brace-iron, as they steady the bolster and prevent it from rocking too much.

Swb is the sway-bar of the forward brace-hounds.

Having thus described my invention, what I claim, and desire to secure by Letters Patent, is the following, viz:

1. The portable shifting-tongue *Pt*, having a recess on the under side to receive the stop-lug *Sl*, the center bar, *Cb*, stop-lug *Sl*, loop-band *Lb*, and socket-band *Sb*, all combined substantially as described.

2. The center bar, *Cb*, provided with loop-band *Lb*, socket-band *Sb*, under-loop staples, *Ls* *Ls'*, draw-bar *Db*, and draw-bolt *Dbt*, all combined substantially as described.

3. The leader-hook *Lh*, the rigid forked center draft-rods, *Dr*, attached to center bar, *Cb*, portable tongue *Pt*, and the front gearing of a wagon, all combined substantially as described.

4. The portable tongue *Pt*, center bar, *Cb*, draft-bar *Db*, draft-rods *Dr*, and eveners, in combination with links *l* and hooks *h*, substantially as described.

5. The pivot rod *Pvr*, center bar, *Cb*, the two connected by joint 3, the rear hounds, 4, 5, and 6, stop-band *Mb*, and set-screw, all combined substantially as described.

In witness whereof I have hereto set my hand this 19th day of July, A. D. 1883.

BENJAMIN C. SHAW.
